UNITED STATES PATENT OFFICE

2,645,404

COLLAPSIBLE COVERED CONTAINER

Kenneth T. Butterly, Kalamazoo, Mich., assignor
to Sutherland Paper Company, Kalamazoo,
Mich., a corporation of Michigan

Application November 21, 1949, Serial No. 128,575

6 Claims. (Cl. 229—36)

1

This invention relates to improvements in a collapsible covered container.

The main objects of this invention are:

First, to provide a covered container or box formed of an integral blank which may be quickly and easily erected and closed and one which, when closed, is secure and rigid and at the same time one in which the cover may be quickly and easily opened and reclosed.

Second, to provide a container having these advantages which may be formed of relatively light paper board or container stock and at the same time is quite rigid when erected and the cover closed and one in which the contents are effectively protected even when the container is subjected to considerable handling.

Objects relating to details and economies of the invention will appear from the description to follow. The invention is defined and pointed out in the claims.

A preferred embodiment of the invention is illustrated in the accompanying drawing, in which:

Fig. 1 is a fragmentary perspective view of a container embodying my invention in closed position, a portion of the cover being broken away to disclose structural details and the relation of certain parts.

Fig. 2 is a perspective view illustrating certain steps of the erecting of the carton and the relation of the parts during such erecting.

Fig. 3 is an enlarged fragmentary vertical section on a line corresponding to line 3—3 of Fig. 1.

Fig. 4 is a plan view of the blank.

I have illustrated my invention as embodied in an elongated container and for convenience in description in the specification and claims, I use the terms "front," "rear" and "end" walls but it will be understood that my invention is equally well adapted to square containers and containers of other shapes and proportions.

The embodiment of my invention illustrated is formed of a single blank illustrated in Fig. 4 and comprises a bottom 1, front wall 2, rear wall 3 hingedly connected to the bottom by hinging score lines conventionally illustrated at 4 and 5. The end walls 6—5 are hingedly connected to the bottom by the score lines 7—7. The cover 8 is hingedly connected to the upper edge of the rear wall 3 by the score line 9.

The cover is provided with a closure flap 10 hingedly connected thereto at 11. The closure flap is provided with locking tongues 12 having locking lugs 13 projecting from their outer side edges. The tongues 12 are spaced longitudinally of the closure flap 10 for purposes which will be pointed out as the description proceeds. The front wall 2 and rear wall 3 are provided with corner flaps 14 hingedly connected thereto at 15.

2

The end walls 6 have cover supporting flaps 16 on their upper edges hingedly connected thereto at 17.

The end walls are provided with slits 18 extending diagonally outward and opening at the end edges of the end walls desirably in alignment with the hinging scores 7. This provides deflectable portions 19 above the slits 18. The end walls have notch-like recesses 20 at their end edges and slits 21 extending diagonally inward providing deflectable portions 22 above the deflectable portions 19.

The corner flaps have upwardly projecting tongues 23 on their side edges and downwardly projecting deflectable tongues 24 spaced from the tongues 23. The slits 18 are adapted to receive the inner edges of the corner flaps when they are disposed in erected position on the outer sides of the end walls. This permits the engagement of the tongues 23 with the portions of the end walls above the slits 18 and the engagement of the downwardly projecting tongues 24 with the end wall portions 22 or the portions below the recesses.

25 The front wall is provided with T-shaped slits 25 adapted to receive the tongues 12. The stem portions 26 of these T-shaped slits open to the top edge of the front wall. When the container is erected with the tongues 23 engaged with the edges of the slits 18 and the tongues 24 engaged over the bottom edges of the recesses, the parts are very effectively interlocked. However, when the cover supporting flaps 16 of the end walls are swung to erected position they engage the upper edges of the corner flaps and further when the tongues 12 are interlocked with the slits 25 the cover supporting flaps 16 are, in effect, held downwardly into retaining engagement with the corner flaps. This results in a structure which, even when made of relatively light stock, is very secure and relatively rigid and at the same time may be quickly opened and reclosed.

45 To open the container it is necessary only to grasp the closure flap 10 between the tongues 12 thereof and pull outwardly and upwardly. This results in retracting the lugs 13 or drawing them toward each other and disengaging them from their interlocking engagement with the slits as is illustrated by dotted lines in Fig. 1 and also in Fig. 3.

50 Applicant desires to point out that his present invention embodies certain features of his application for patent, Serial No. 638,165, filed December 29, 1945, on which Patent 2,488,703 issued November 22, 1949; and also is an embodiment and adaptation of certain features of the joint application of applicant and Richard C. Stenger, Serial No. 48,666, filed September 10, 1948, on which Patent 2,488,705 issued November 22, 1949.

55 60 I have illustrated and described my invention

as a highly practical commercial embodiment thereof. I have not attempted to illustrate or describe other adaptations as it is believed that this disclosure will enable those skilled in the art to embody or adapt my invention as may be desired.

Having thus described my invention, what I claim as new and desire to secure by Letters Patent is:

1. A container comprising bottom, front, rear and end walls hingedly connected to the bottom, and a cover hingedly connected to the top edge of the rear wall, the cover having means for detachably connecting the cover to the front wall, the front and rear walls having corner flaps hingedly connected thereto, the end walls being provided with cover supporting flaps at their outer ends and having slits extending diagonally inward from their bottom edges, said end walls having recesses in their end edges and slits extending downwardly from the bottoms of the recesses, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

2. A container comprising bottom, front, rear and end walls hingedly connected to the bottom, and a cover hingedly connected to the top edge of the rear wall, the cover having means for detachably connecting the cover to the front wall, the front and rear walls having corner flaps hingedly connected thereto, the end walls having slits extending diagonally inward from their bottom edges, said end walls having recesses in their end edges and slits extending downwardly from the bottoms of the recesses, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

3. A container comprising bottom, front, rear and end walls hingedly connected to the bottom, and a cover hingedly connected to the top edge of the rear wall, the cover having means for detachably connecting the cover to the front wall, the front and rear walls having corner flaps hingedly connected thereto, the end walls being provided with cover supporting flaps at their outer ends and having slits extending diagonally inward from their bottom edges, said end walls having recesses in their end edges adapted to receive the inner edges of the corner flaps when the container is erected, said corner flaps having upwardly projecting tongues engageable with the upper edges of said slits of the end walls and having downwardly projecting tongues spaced from the upwardly projecting tongues engageable over the bottom edges of said recesses in said end walls.

the upwardly projecting tongues engageable over the bottom edges of said recesses in said end walls.

5. A container comprising bottom, front, rear and end walls hingedly connected to the bottom, and a cover hingedly connected to the top edge of the rear wall, the cover having means for detachably connecting the cover to the front wall, the front and rear walls having corner flaps hingedly connected thereto, the end walls having slits extending diagonally inward from their bottom edges, said end walls having recesses in their end edges adapted to receive the inner edges of the corner flaps when the container is erected, said corner flaps having upwardly projecting tongues engageable with the upper edges of said slits of the end walls and having downwardly projecting tongues spaced from the upwardly projecting tongues engageable over the bottom edges of said recesses in said end walls.

20. 5. A container comprising bottom, front, rear and end walls hingedly connected to the bottom, and a cover hingedly connected to the top edge of the rear wall, the cover having means for detachably connecting the cover to the front wall,

25. 5. A container comprising bottom, front, rear and end walls hingedly connected to the bottom, and a cover hingedly connected to the top edge of the rear wall, the cover having means for detachably connecting the cover to the front wall, the front and rear walls having corner flaps hingedly connected thereto, the end walls being provided with cover supporting flaps at their outer ends and having slits extending diagonally inward from their bottom edges, the portions of

30. the end walls above the slits being inwardly deflectable, said end walls having recesses in their end edges and slits extending downwardly from the bottoms of the recesses, the first mentioned slits in said end walls being adapted to

35. receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

40. 6. A container comprising bottom, front, rear and end walls hingedly connected to the bottom, the front and rear walls having corner flaps hingedly connected thereto, the end walls having slits extending diagonally inward from their bottom edges, said end walls having recesses in their end edges, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

45. 6. A container comprising bottom, front, rear and end walls hingedly connected to the bottom, the front and rear walls having corner flaps hingedly connected thereto, the end walls having slits extending diagonally inward from their bottom edges, said end walls having recesses in their end edges, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

50. 6. A container comprising bottom, front, rear and end walls hingedly connected to the bottom, the front and rear walls having corner flaps hingedly connected thereto, the end walls having slits extending diagonally inward from their bottom edges, said end walls having recesses in their end edges, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

55. 6. A container comprising bottom, front, rear and end walls hingedly connected to the bottom, the front and rear walls having corner flaps hingedly connected thereto, the end walls having slits extending diagonally inward from their bottom edges, said end walls having recesses in their end edges, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.

60. 6. A container comprising bottom, front, rear and end walls hingedly connected to the bottom, the front and rear walls having corner flaps hingedly connected thereto, the end walls having slits extending diagonally inward from their bottom edges, said end walls having recesses in their end edges, the first mentioned slits in said end walls being adapted to receive the inner edges of the corner flaps when the container is erected, said corner flaps having upwardly projecting tongues engageable with the upper edges of said first mentioned slits of the end walls and having downwardly projecting tongues spaced from the upwardly projecting tongues engageable over the bottom edges of said recesses in said end walls, the slits extending downwardly from the said recesses permitting deflection of portions of the end walls below the recesses facilitating engagement of the downwardly projecting tongues therewith.
